US00D772474S

(12) **United States Design Patent** (10) Patent No.: **US D772,474 S**
Chang et al. (45) Date of Patent: **** Nov. 22, 2016**

(54) **LIGHTING FIXTURE**

- (71) Applicant: **Atlas Lighting Products, Inc.**,
Burlington, NC (US)
- (72) Inventors: **Cheng S. Chang**, Elon, NC (US); **Scott T. Ellingson**, Graham, NC (US); **James H. Bennett**, Greensboro, NC (US); **R. Samuel Hunt, III**, Burlington, NC (US)
- (73) Assignee: **Atlas Lighting Products, Inc.**,
Burlington, NC (US)
- (**) Term: **15 Years**
- (21) Appl. No.: **29/539,022**
- (22) Filed: **Sep. 10, 2015**

Related U.S. Application Data

- (63) Continuation of application No. 29/494,228, filed on Jun. 18, 2014, now Pat. No. Des. 740,997, which is a continuation of application No. 29/478,845, filed on Jan. 9, 2014, now Pat. No. Des. 710,530.

Primary Examiner — Cynthia Ramirez*Assistant Examiner* — Llorellys Martinez-Rivera*(74) Attorney, Agent, or Firm* — Womble Carlyle Sandridge & Rice, LLP(57) **CLAIM**

The ornamental design for a lighting fixture, as shown and described.

DESCRIPTION

FIG. 1 is a right side view of a lighting fixture showing our new design;

FIG. 2 is a top view thereof;

FIG. 3 is a rear view thereof;

FIG. 4 is a front view thereof; and,

FIG. 5 is a front right perspective view thereof.

The dash-dot lines in FIGS. 1 through 3 and 5, immediately adjacent to the shaded area, illustrate unclaimed boundaries of the design. The other broken lines in the drawings illustrate environmental subject matter only and form no part of the claimed design.
